UNITED STATES PATENT OFFICE.

MARCUS L. DOUGHTY AND JOHN W. FERGUSON, OF CHICAGO, ILLINOIS.

TIME-CONTROLLED MECHANISM.

1,251,760.

Specification of Letters Patent.

Patented Jan. 1, 1918.

Application filed May 5, 1916. Serial No. 95,685.

To all whom it may concern:

Be it known that we, MARCUS L. DOUGHTY, a citizen of the United States, residing at Chicago, in the county of Cook and State of Illinois, and JOHN W. FERGUSON, a citizen of the United States, residing at Chicago, in the county of Cook and State of Illinois, have invented certain new and useful Improvements in Time-Controlled Mechanism, 10 of which the following is a specification.

Our invention relates in general to time-controlled mechanism, and more particularly to means for automatically effecting the operation of a device after the lapse of a 15 predetermined interval of time.

In the use of many machines it is desirable to control the operation at a predetermined time, or after a certain interval of time, and in some systems it is necessary 20 that a signal should be given at a certain hour. For instance, it frequently happens that a single attendant is in charge of the operation of several washing machines, and one of his duties is, after the clothes have 25 been sufficiently washed, to open the outlet valve of the tank of each machine and let the water run out preparatory to filling the tank with clean water to receive another supply of articles. As the attendant cannot 30 give his entire attention to each machine, it is impractical for him to open the valve of each machine at the exact time the articles therein have been sufficiently washed, and hence the charge of articles in each machine 35 necessarily remains therein longer than is necessary, and the capacity of the machine is therefore not fully available, and, further, the time of the attendant is wasted while he waits for the discharge of the water from 40 the tank of each machine after he has opened the outlet valve thereof.

The primary object of our invention is to provide mechanism for automatically controlling the operation of a machine, or for 45 automatically operating a signal, at a predetermined time, or after the lapse of a definite interval of time.

A further object of our invention is to provide an improved electrically-actuated 50 system for effecting a given operation at a given time.

A still further object of our invention is to provide a time-controlled mechanism for 55 automatically opening the outlet valve of a washing machine after the articles therein

have been subjected to the desired washing action.

Our invention will be more fully disclosed hereinafter with reference to the accompanying drawings, in which the same is illustrated as embodied in a convenient and practical form, and in which—

Figure 1 is a somewhat diagrammatic view illustrating our invention as applied to the outlet valves of a plurality of washing 65 machines;

Figs. 2 and 3 are detail views of the tripping device for permitting the valve to open;

Fig. 4 is a view showing a modified mechanical means for opening the valve; and

Fig. 5 is an elevational view of the means shown in Fig. 3.

Similar reference characters are used to designate similar parts in the several figures 75 of the drawings.

Reference letter A designates a master clock for making a plurality of electrical contacts at predetermined intervals of time, as, for instance, by providing fixed contacts 80 spaced five minutes apart around the dial with which successively engages the minute hand a of the clock. The fixed contacts in the master clock are each separately connected with corresponding fixed contacts on 85 a plurality of secondary circuit controllers such as B' and B², preferably located adjacent the machines or mechanism the operations of which are to be separately controlled by the master clock.

C designates any suitable source of electricity, such, for instance, as a transformer, connected by a lead c with the minute hand a of the master clock, and by the lead c' with electrically actuated devices D' and D² 95 adjacent the respective machines which are to be controlled. Each of these devices comprises a magnet and an armature, the opposite terminal of the magnet winding from that with which the lead c' is connected being connected by a lead d' with a fixed contact d². Located adjacent the fixed contact d² is another fixed contact d², which is connected by a lead d² with the movable contact b' of the secondary controller B'. The electrical connections and mechanism connected with each of the secondary controllers are the same, and hence a description of those controlled by one of the secondary controllers will be sufficient.

A lead e' is electrically connected with each of the branch leads d^4 extending from the devices D' and D^2 and leads to a master signal E , such for instance, as a bell. The circuit through the master signal is continued through the lead e to a fixed contact c^4 located adjacent another fixed contact c^3 connected to the conductor c' which in turn leads to the source of electricity C . Located adjacent the fixed contact c^4 is a fixed contact f^2 connected by a lead f' with a secondary signal, such, for instance, as a light F' located adjacent the particular machine the operation of which is controlled by the secondary clock. The circuit through the secondary signal F' is completed through the lead f^3 to the lead C^2 , and thence to the source of electricity C .

Located adjacent the armature of the device D' is a tripping device comprising a plunger G' located in a casing G and having a trigger g adapted, upon rotation of the plunger, to engage within a notch in the casing, and when in such position being in the path of a hammer d carried by the armature of the device D' . Located within the casing G , beneath the plunger G' , is a spring G^2 . A rod g' is connected with the plunger G' , and is pivotally connected with a lever H which carries contacts H' and H^2 insulated from each other, the forward contact serving when the plunger is in the depressed position shown in Fig. 1 to electrically connect the fixed contacts d^2 and d^3 , and the latter contact H^2 serving when the plunger is released and the lever H oscillated to connect electrically the fixed contacts c^3 , f^2 , and c^4 .

The plunger G' is mechanically connected with the mechanism the operation of which is to be controlled, such, for instance, as the outlet valve P of the tank M of a washing machine. In the embodiment of our invention shown in Figs. 1 and 2 the rod g' is connected by a chain k with a lever K , fulcrumed upon a bracket L projecting from the casing L' of the outlet valve. The lever K is provided with a lug K' , against which rests the upper end of the link n , through a slot in which the end of the lever K extends. This link is pivotally connected with a detent N , fulcrumed at n' upon the valve casing L' . This detent—in the position thereof shown in Fig. 1—overlies the end of a hand lever O , fulcrumed at o upon the bracket L . The end of the lever O opposite to the handle is pivotally connected by a rod p with the valve P . A spring o' is interposed between the lever O and a fixed support, such, for instance, as the bracket L , the tension of which tends to oscillate the lever in the direction to open the valve.

The operation of the embodiment of our invention above described is as follows: The movable contact b' of the secondary control-

ler B' is moved into engagement with a fixed contact corresponding with a fixed contact on the master clock A , which will be engaged by the minute hand a of the master clock after the lapse of the desired interval of time. Assuming that it is desired that the valve of the washing machine should be opened after ten minutes, the movable contact b' is moved into engagement with the fixed contact 6 , and hence when the minute hand of the master clock engages the fixed contact 6 the following circuit will be closed: from the source of electricity C through the lead c , minute hand a , fixed contact 6 in the master clock to the fixed contact 6 on the secondary, thence through movable contact b' , lead d^4 , fixed contact d^3 , contact H' , fixed contact d^2 , lead d' , the winding of the device D' , lead c' , back to the source of electricity C . The said circuit energizes the coil of the device D' so that the armature is attracted and the hammer d disengages the trigger g from its set position, thereby permitting the spring G^2 to elevate the plunger and oscillate the lever H so as to break the circuit between the fixed contacts d^2 and d^3 , and electrically connect the three contacts c^4 , f^2 , and c^3 through the contact H^2 . Circuits are then closed to the master signal E , and also to the secondary signal F' of the particular secondary clock B' , such circuits being as follows: from the source of electricity C to lead c' , to fixed contact c^3 , movable contact H^2 , fixed contact c^4 , lead e , signal E , lead e' , movable contact b' and fixed contact 6 of the secondary controller to fixed contact 6 and movable contact a of the master clock, back to the source of electricity C , thereby operating the master signal E . The secondary signal F' is energized as follows: C , lead c^2 , lead f^3 , F' , lead f' , fixed contact, f^2 , movable contact H^2 , fixed contact c^3 , lead c' , back to C . It will be observed that the master signal is only actuated as long as the movable contact a of the master clock is in engagement with the fixed contact through which the circuit has been closed, while the circuit through the secondary signal remains closed, and the signal continues to be actuated until the operator sets the device by forcing downwardly the plunger G' and thereby oscillating the lever H to break the circuit through the contacts c^3 and f^2 .

The release of the plunger G' also effects the mechanical operation desired, as, for instance, opening the valve P , inasmuch as the upward movement of the plunger G' oscillates the lever K so that the shoulder K' swings from under the link n , allowing the detent N to be swung out of engagement with the end of the lever O by reason of the upward pressure upon the end of such hand lever, due to the tension of the spring o' . The lever is consequently oscillated so as to

elevate the valve P from its seat Q through the medium of the rod p. The water is thereby discharged from the tank of the washing machine M.

- 5 From the foregoing description it will be seen that when the predetermined interval of time has elapsed the valve is opened, and simultaneously therewith a master signal is given to call attention of the attendant to 70 the fact that one of the machines has been operated, the particular machine which has been operated being designated by the secondary signal F' located at such machine. After the water has been discharged from 75 the tank of the machine the attendant depresses the plunger G, and engages the trigger g thereof with its retaining notch so as to be in position to be again tripped by the hammer d of the device D'. The hand lever 80 20 O is oscillated against the tension of the spring o' so as to seat the valve, and the 85 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900
- by a downward push on the handle p², thereby elevating the weight and moving the chain R relatively to the sheave r, thus rotating the latter and with it the disk S until the notch therein is engaged by the trigger t. When the circuit is closed through the secondary, so as to release the plunger in the manner above described in connection with Figs. 1 and 2, upward pull on the chain k releases the trigger from the notch s in the disk S, thereby permitting the weight to descend and open the valve.
- While we have illustrated and described our invention as embodied in apparatus for separately controlling the opening of the valves of washing machines after predetermined intervals of time, yet it will be understood that our invention is not limited to such application, but may be used separately and automatically to control at predetermined intervals the operations of a plurality of various devices.
- We claim:—
1. The combination with a plurality of machines, of an operating part controlling each of said machines and adapted for selective movement into alternate positions, means for automatically and independently moving each of said operating parts into a selected position at any predetermined time, an individual signal for each of said machines, means for operating said signal upon movement of said operating part into said position, a master signal, and means for operating said master signal upon operation of any of said individual signals.
  2. The combination with a plurality of machines, of an operating part controlling each of said machines and adapted for selective movement into alternate positions, means for automatically and independently moving each of said operating parts into a selected position at any predetermined time, a signal light for each of said machines, an electric circuit, means for closing said circuit through said light while said operating part is in said selected position, a master signal, and means for closing said circuit through said master signal upon operation of any of said signal lights.
  3. The combination with a plurality of washing machines, of an outlet valve for each of said machines, means for automatically and independently moving each of said valves into a selected position at any predetermined time, an individual signal at each of said machines, means for operating said signal when the valve of said machine is moved to said selected position, a master signal, and means for operating said master signal upon operation of any of said individual signals.
  4. The combination with a plurality of washing machines, of an outlet valve for each of said machines, means for automati-

- 2
- cally and independently moving each of said valves into a selected position at a pre-determined time, a signal light at each of said machines, means for operating said 5 light while said valve is in said selected position, a signal bell, and means for ringing said bell for a predetermined length of time upon operation of any of said signal lights.
- 10 5. In a time-controlled apparatus, the combination of a plurality of machines, a source of current, means electrically connected with said source for automatically and independently controlling the operation 15 of each of said machines at a predetermined time, a master signal, means for connecting said master signal in series with said controlling means, a secondary signal at each of said machines, and means for connecting 20 said secondary signal with said source in parallel with said controlling means upon operation of said machine.
6. In combination with a plurality of washing machines, an outlet valve for each of said machines, a source of current, means 2 electrically connected with said source for automatically and independently moving each of said valves to a selected position at a predetermined time, a master signal, means for connecting said master signal in 25 series with said valve-moving means, a secondary signal at each of said machines, and means for connecting said secondary signal with said source in parallel with said valve-moving means upon movement of said valve 30 to said selected position.
- In testimony whereof, we have subscribed our names.
- MARCUS L. DOUGHTY.
JOHN W. FERGUSON.
